(57) **CLAIM**

The ornamental design for a co-axial cable connector, as shown and described.

DESCRIPTION

FIG. 1 is a perspective view of a new and ornamental design for a co-axial cable connector, the internal details thereof being illustrated in phantom for environmental purposes only and form no part of the claimed design;

FIG. 2 is a side elevational view thereof;

FIG. 3 is a nut end view thereof; and,

FIG. 4 is a cable end view thereof.

1 Claim, 3 Drawing Sheets

FIG. 1

FIG. 2

FIG. 3

FIG. 4
